UNITED STATES PATENT OFFICE.

DAVID C. LEWIS, OF YOUNGSTOWN, OHIO.

SHAMPOO-TRAY.

1,111,311.

Specification of Letters Patent. Patented Sept. 22, 1914.

Application filed June 15, 1914. Serial No. 845,183.

To all whom it may concern:

Be it known that I, DAVID C. LEWIS, a citizen of the United States, residing at Youngstown, in the county of Mahoning and State of Ohio, have invented certain new and useful Improvements in Shampoo-Trays, of which the following is a specification.

This invention relates to shampoo trays or boards, and one of the principal objects of the invention is to provide a device of simple construction for supporting the head and hair of a lady during the operation of shampooing, and another object of the invention is to provide a head rest on the tray or board which will support the head in a comfortable position and which will work freely upon its pivotal point to conform to the position of the head.

Another object of the invention is to provide a shampoo board or tray which can be adjusted vertically and at various angles to any position required for supporting the head and hair of a person during the shampooing and drying operation of the hair.

These and other objects may be attained by means of the construction illustrated in the accompanying drawing, in which,

Figure 1 is a side elevation of a shampoo board or tray made in accordance with this invention, Fig. 2 is a top plan view of the board or tray, Fig. 3 is a sectional view taken on the line 3—3 of Fig. 1, Fig. 4 is a longitudinal section of the board taken on the line 4—4 of Fig. 2, and Fig. 5 is a detail perspective view of the head rest.

Referring to the drawing, the numeral 1 designates a standard or support mounted upon suitable legs 2, and mounted telescopically upon the standard 1 is the adjustable member 3 provided with a binding screw 4 for holding the two members in an adjusted relation. The upper end of the member 3 is provided with a corrugated head 5 adapted to cooperate with the similar corrugated head 6 underneath the board or tray, and said two heads 5 and 6 being adjustably held in engagement by means of the binding screw 7 to adjust the tray at any desired inclination. The board or tray 8 is provided with side flanges 9, and connected to the underside of the tray by means of a suitable shank 10 is the corrugated head 6. The front end of the board or tray 8 is cut away

as at 11 to accommodate the neck of the customer and to permit the hair to lie on the tray 8 and drain off.

Pivoted at a slight distance from the neck opening 11 is a head rest 12, said head rest being curved to receive the back of the head or neck and provided with spaced lugs 13 on the underside thereof, said lugs being pivoted upon a bracket or projecting stud 14 rising from the upper surface of the tray, as shown more clearly in Fig. 3.

A pivoted gate or strap 15 is pivoted at 16 at one side of the neck opening 11 and at the opposite side may be provided with a pin or other fastening 17, said gate being designed for supporting an apron or bib to prevent the wearer from getting wet during the shampoo operation.

From the foregoing it will be obvious that a shampoo board or tray made in accordance with this invention can be readily adjusted as to height and as to inclination to suit the position of the customer or person having their hair shampooed, and that the head rest will assume a proper position to support the head comfortably in place, and that the entire device is simple in construction and can be manufactured at comparatively low cost.

Various changes may be made in the details of construction without departing from the spirit and scope of the invention as defined in the claim.

What is claimed is:

The herein described shampoo board or tray comprising a standard, means for adjusting said standard vertically, a tray mounted pivotally upon said standard, means for adjusting said tray at various inclination relative to the standard, said tray being gradually reduced in width at its outer end, and having a curved head rest pivoted thereon, upwardly turned flanges at the side of said tray, the latter being provided with a neck opening at one end and a pivoted gate for said neck opening.

In testimony whereof I affix my signature in presence of two witnesses.

DAVID C. LEWIS.
